UNITED STATES PATENT OFFICE.

FRANK. M. WHITEMAN, OF CANTON, OHIO.

DESIGN FOR A BASE FOR A GAME APPARATUS.

SPECIFICATION forming part of Design No. 23,647, dated September 18, 1894.

Application filed April 6, 1894. Serial No. 506,635. Term of patent 7 years.

To all whom it may concern:

Be it known that I, FRANK. M. WHITEMAN, a citizen of the United States, residing at Canton, in the county of Stark and State of Ohio, 5 have invented and produced a new and original Design for the Base of a Game Apparatus, of which the following is a specification.

Reference is to be had to the accompanying drawing, forming a part of this specification, 10 in which the figure represents a perspective view of the base of a game apparatus embodying my new design.

The design relates to the class of devices by which a ball is to be thrown or tossed by a 15 trap.

The leading feature of my design consists in the novel configuration of the base of the apparatus. Thus the body *a* of the base is cylindrical in shape exteriorly and interiorly 20 and the sides are spaced apart at the rear, and from the top of the body at such open

rear depart the lines of the member *b* simulating the stock and trail of a gun carriage, said lines continuing outward and downward as shown. The bottom lines of the member *b* 25 curve downward and then outward from the body, while the top lines depart outwardly without downward inclination and then curve downwardly and outwardly. Further, the outer end of the arm is broadened, while the 30 inner end has its greater dimensions disposed vertically and presents a furcated conformation. The lines of the trap *a* depart from the base at a point adjacent to the body and form an angle with the arm *b* as shown. 35

I claim—

The design for the base of a game apparatus herein shown and described.

FRANK. M. WHITEMAN.
